POLYNITRO NITRATE COMPOUNDS AND
METHOD OF PREPARATIONMilton B. Frankel, Pasadena, Calif., assignor to Aerojet-
General Corporation, Azusa, Calif., a corporation of
OhioNo Drawing. Filed Feb. 18, 1958, Ser. No. 715,988
8 Claims. (Cl. 260—467)

This invention relates to new and useful polynitro nitrates and a method for their preparation. In particular it relates to aliphatic polynitro nitrates having the general formula:

wherein A is an alkylene radical and Z is a nitromethylene, dinitromethylene or nitramine radical.

The nitro compounds of this invention are useful as high explosives and can be used in any conventional explosive missile, projectile, rocket, or the like, as the main explosive charge. An example of such a missile is disclosed in U.S. Patent No. 2,470,162, issued May 17, 1949. One way of using the high explosives in a device such as that disclosed in U.S. Patent No. 2,470,162 is to pack the crystalline explosive in powder form into the warhead of the missile. Alternatively, the crystals can be first pelletized and then packed. A charge thus prepared is sufficiently insensitive to withstand the shock entailed in the ejection of a shell from a gun barrel or from a rocket launching tube under the pressure developed from ignition of a propellant charge, and can be caused to explode on operation of an impact- or time-fuse mechanism firing a detonating explosive such as lead azide or mercury fulminate.

The compounds of this invention are readily prepared by reacting the corresponding alcohols with nitric acid, in accordance with the general reaction scheme set forth below:

wherein A and Z are as defined above.

The nitro alcohols used as starting materials in this invention are readily prepared by the reduction of the corresponding acyl halides with sodium borohydride, as disclosed in assignee's copending application No. 392,471, now abandoned, filed November 16, 1953.

To more clearly illustrate this invention, the following examples are presented. It is to be understood, however, that these examples are presented merely as a means of illustration and are not intended to limit the scope of the invention in any way.

EXAMPLE I

Preparation of 4,4,6,8,8-pantanitro-1,11-undecane dinitrate

The solid 4,4,6,8,8-pantanitro-1,11-undecanediol was added to a tenfold excess of 100% commercial nitric acid at ice-bath temperature. The acid solution was stirred for a period of 15 minutes at a temperature of about 5–10° C. and then poured over ice. The white solid was collected, washed with water and dried in vacuum over potassium hydroxide. The product was recrystallized from methanol in 96.1% yield and exhibited a melting

2

point of 73–75° C. The elemental analysis of the compound is as follows:

Calculated for $\text{C}_{11}\text{H}_{17}\text{N}_7\text{O}_{16}$: C, 26.25%; H, 3.41%; N, 19.48%. Found: C, 26.79%; H, 3.64%; N, 19.18%.

5 The explosive values of the product were calculated to be:

Lead block value 126 T.N.T.=100
Ballistic mortar value 137 T.N.T.=100

EXAMPLE II

Preparation of 4,4,6,6,8,8-hexanitro-1,11-undecane dinitrate

By reacting 4,4,6,6,8,8-hexanitro-1,11-undecanediol with nitric acid in accordance with the procedure in Example I, 4,4,6,6,8,8-hexanitro-1,11-undecane dinitrate having a melting point of 100–101° C. was obtained in 95.2% yield. The elemental analysis of the product is as follows:

Calculated for $\text{C}_{11}\text{H}_{16}\text{N}_8\text{O}_{18}$: C, 24.09%; H, 2.94%; N, 20.44%. Found: C, 24.54%; H, 2.99%; N, 19.91%. The explosive values of the product were calculated to be:

Lead block value 138 T.N.T.=100
Ballistic mortar value 143 T.N.T.=100

EXAMPLE III

Preparation of 4,4,6,8,8-pantanitro-6-aza-1,11-undecane dinitrate

30 By reacting 4,4,6,8,8-pantanitro-6-aza-1,11-undecanediol with nitric acid in accordance with the procedure in Example I, 4,4,6,8,8-pantanitro-6-aza-1,11-undecane dinitrate having a melting point of 133–135° C. was obtained in 95.0% yield. The elemental analysis of the product is as follows:

Calculated for $\text{C}_{10}\text{H}_{16}\text{N}_8\text{O}_{16}$: C, 23.82%; H, 3.20%; N, 22.22%. Found: C, 23.88%; H, 2.96%; N, 22.15%. The explosive values of the product were calculated to be:

Lead block value 135 T.N.T.=100
Ballistic mortar value 142 T.N.T.=100

I have also found that the homologues of the above compounds, namely, 3,3,5,5,7,7-hexanitro-1,9-nananediol, 3,3,5,7,7-pantanitro-1,9-nananediol and 3,3,5,7,7-pantanitro-5-aza-1,9-nananediol also react with nitric acid forming the nitrate esters 3,3,5,5,7,7-hexanitro-1,9-nanane dinitrate, 3,3,5,7,7-pantanitro-1,9-nanane dinitrate, and 3,3,5,7,7-pantanitro-5-aza-1,9-nanane dinitrate.

50 It is apparent that any member of the nitro-containing aliphatic nitrate series may be prepared by merely selecting the appropriate nitro-containing alcohol and reacting it with nitric acid, in accordance with the teachings of this invention.

This application is a continuation-in-part of my co-pending U.S. Patent Application Ser. No. 409,263, now abandoned, filed February 9, 1954.

I claim:

1. As compositions of matter, the aliphatic polynitro-nitrates having the formula:

wherein A is a lower alkylene radical and Z is a radical selected from the group consisting of nitromethylene, dinitromethylene and nitramine radicals.

2. As a composition of matter, 4,4,6,8,8-pantanitro-1,11-undecane dinitrate having the structural formula:

3. As a composition of matter, 4,4,6,6,8,8-hexanitro-1,11-undecane dinitrate having the structural formula:

4. As a composition of matter, 4,4,6,8,8-pantanitro-6-aza-1,11-undecane dinitrate having the structural formula:

5. The method of preparing aliphatic polynitronitroates having the formula:

5

which comprises reacting nitric acid with a nitro-containing diol having the formula:

wherein A is a lower alkylene radical and Z is a member of a group consisting of nitromethylene, dinitromethylene and nitramine radicals.

6. The method of preparing 4,4,6,8,8-pantanitro-1,11-undecane dinitrate which comprises reacting 4,4,6,8,8-hexanitro-1,11-undecanediol with nitric acid.

7. The method of preparing 4,4,6,8,8-hexanitro-1,11-undecane dinitrate which comprises reacting 4,4,6,8,8-hexanitro-1,11-undecanediol with nitric acid.

8. The method of preparing 4,4,6,8,8-pantanitro-6-aza-1,11-undecane dinitrate which comprises reacting 4,4,6,8,8-pantanitro-6-aza-1,11-undecanediol with nitric acid.
